UNITED STATES PATENT OFFICE.

BEN K. FORD, OF DETROIT, MICHIGAN.

SHEAR.

1,185,787.

Specification of Letters Patent. Patented June 6, 1916.

Application filed February 26, 1913, Serial No. 750,832. Renewed March 27, 1916. Serial No. 87,089.

To all whom it may concern:

Be it known that I, BEN K. FORD, a citizen of the United States, and a resident of Detroit, in the county of Wayne and State of Michigan, have invented a new and useful Shear, of which the following is a specification.

This invention relates to means for cutting sheets of plaster board, paper or other material which is produced in large, continuous sheets into predetermined lengths, and its object is to provide a shear which shall be simple in operation, which shall be adapted to sever the moving sheet by traveling with it during the shearing operation, and which shall automatically return to starting position.

This invention consists in combination with a self-contained vertically movable shear mounted on proper wheels and a track for the same, of a cylinder and piston adapted to move said shear back and forth along the track, and means under the control of the sheet as it passes between the shear members for actuating the shear and for controlling the fluid which moves the shear along its track.

In the accompanying drawings Figure 1 is a side elevation of the shear. Fig. 2 is a vertical section of a brake. Fig. 3 is a horizontal section on the line 3—3 of Fig. 1. Fig. 4 is a diagrammatic view showing a portion of the electric wiring. Fig. 5 is a longitudinal section of the pneumatic cylinder. Fig. 6 is a vertical, longitudinal section of the entire construction. Fig. 7 is an elevation of the controlling shaft. Fig. 8 is a detail on a larger scale of a portion of the controlling mechanism. Figs. 9 and 10 are elevations of the main switch. Fig. 11 is an elevation of the second switch and Fig. 12 is a view of the same looking up from the bottom. Fig. 13 is a section on the line 13—13 of Fig. 14. Fig. 14 is a vertical section 45 through the clutch on the main shaft of the shear. Fig. 15 is an end elevation of the shear.

Similar reference characters refer to like parts throughout the several views.

50 Plaster board, heavy paper and other fibrous materials are continuously produced in long sheets or bands of considerable width. It is desirable that the movement of this wide band of material shall not be inter-

rupted, and it is also desirable that this material shall be cut into predetermined lengths so that it can be handled, and that these lengths be approximately correct so that a second shearing to length is unnecessary. It is also desirable that the cut edges shall 60 be smooth, as any breaking or cracking of these edges means a loss of material. The construction shown in the accompanying drawings, in which the shear is connected to the paper and moves with it during the 65 shearing operation and immediately afterward releases the paper so that it can again move the desired distance before the shear again operates, accomplishes the desired result. It will be understood that the severed 70 sheets of fibrous material will be removed by workmen immediately so that the parts may resume normal position at once after the shearing operation.

In the drawings a pair of ways 1 are 75 shown, having V-shaped grooves 2 to receive the wheels 3 rigidly secured on the shafts 4. The side frames 5 of the press have bosses 6 in which these shafts are mounted. Vertically 80 slidable in the side frames 5 are the plates 7 and 8, the latter carrying the movable shear member 9. A main shaft 10 extends across between the side frames 5 and carries cranks 11 on which are mounted the connecting rods 12, which rods extend to the pins 13 carried by the vertically movable slide 8. On this shaft are mounted the large gear 15, the brake drum 16 and the cam 17. A strap 18 extends around the brake drum and is adjusted by the bolt 19 and supported by the 90 pin 20 so that a constant drag on the shaft is produced in order to stop the same as soon as the power is disconnected. The large gear 15 is not secured to the main shaft but is provided with an annular flange 22, shown 95 in Fig. 13, having interior teeth 23. A ring 24 is secured to the shaft by means of a key 25 and carries a pawl 26 normally held outward by means of a spring 27. Mounted in the side frame 5 is a pin 28 normally held 100 outward in the path of the pawl 26 by means of a spring 29. A bell-crank lever is mounted on the pin 30 and has a bifurcated arm 32 engaging the pin 33 on the pin 28, and also having an armature 34 which may be attracted by the electro-magnet 35. A wire 36 leads to this electro-magnet from the secondary switch shown in Figs. 11 and 12.

A second shaft 38 is mounted in the frames and has secured to it the gear 39 and the pinion 40, which latter meshes with the big gear 15 on the crank shaft. A third shaft 5 41 is mounted in the frames and carries a pinion 43 which meshes with the gear 39 and also carries a gear 44 which meshes with the pinion 45 on the driving shaft of the motor 46. This motor is constantly in motion so 10 that the main gear 15 runs at all times.

The sheet of fibrous material is indicated by the dotted line 59 in Fig. 6 and passes through between the shear members 9 and 47, which latter are carried by the cross bars 15 48 as shown in Fig. 6. The vertically slide- 20 able plate 7 is carried by links 49 and arms 50 on the shaft 51. A counter-weight 53 is mounted on the outer end of the arm 54, also secured to this shaft. A third arm 56^a is 25 mounted on this shaft and carries a roller 57^a which engages the cam 17 as shown in Fig. 1. When the shaft 10 begins to re- 30 volve, the first movement will be to depress the arm 56^a and thereby the plate 7, thus gripping the sheet of fibrous material be- 35 tween this plate and the lower shear mem- 40 ber 47 directly beneath it. Immediately thereafter the cranks will depress the other plate 8 and cause the shear member 9 to pass 45 down between the shear members 47, thus severing the paper along smooth and straight lines.

The fibrous material which this machine is adapted to cut into sheets of predetermined length has considerable stiffness, but 35 not always sufficiently so that it can be relied upon to move the shear on its ways. In order to take up this endwise stress on the fibrous material, a cylinder and piston rod 40 are provided and the motive power may be supplied by any fluid under pressure, but preferably by compressed air. Referring to Figs. 5 and 6, the cylinder 55 will be seen mounted between the tracks 1 by means of 45 the bars 61, which cylinder has a rear head 56 and a front head 57 provided with a stuffing box 58 in which is slidable the piston rod 59. On the inner end of the piston rod is mounted the piston 60 having rings 62 50 and a piston head 63. The piston is preferably provided with a boss 64 over which a washer 65, preferably leather, is held by means of the nut 66 which may be screwed onto the piston rod. The piston head 63 55 may have a similar boss 67 to receive the washers 68, held in place by means of the metal washer 69 and screw 70. The head 56 has a depression 72 while the head 57 has a depression 73, which depressions constitute 60 dashpots that receive the bosses and prevent the piston striking against the cylinder heads. The cylinder is formed with a well known valve chamber 75 into which a pipe 76 connects. Ports 77 and 78 connect to the 65 ends of the cylinder and a valve rod 79 car-

ries the pistons 80 and 81. A spring 83 is adapted to pull the valves to the left in Fig. 5.

A bar 85 extends between the sides 5 of this shear and into this the outer end of the piston rod 59 is secured as shown in Fig. 6. On the tracks 1 are mounted the bearings 87 in which the cross shaft 88 is revolvably mounted. This shaft supports the levers 89 and 90 and on this shaft may be wound a 75 spring 91 to counterbalance the pull of the spring 83. These two springs are preferably of the same tension so that the levers 89 and 90 and the valves 80 and 81 will remain in any position where they may be placed. As 80 it may be desired to cut the sheets of different lengths, the bearings 87 may be adjustably secured to the tracks 1 by means of the hooks 93, and the rod 79 may pass through an eye 94 carried by the lever 89 as shown 85 in Fig. 8, the rod 79 being secured by means of a set screw 95.

When the sheet 59^a has been produced of sufficient length to strike the lever 89, this lever will be swung outward, that is to the 90 left in Fig. 6, and the valve rod 79 pushed inwardly until the valves are in the position shown in Fig. 5. This will cause pressure in the outer end of the cylinder and move the piston and piston rod to the left in Fig. 6, 95 causing the shear and the sheet to travel together. The stiffness and tensile strength of the sheet are such that should the pressure in the cylinder be less or more than sufficient to alone move the shear, the strength 100 of the sheet will cause them to move together. Immediately after the shear begins to move longitudinally of the tracks, the shearing operation takes place.

As was stated before, the gear 15 revolves 105 constantly, and the pawl 26 is held out of engagement with the teeth 23 in the manner shown in Fig. 13. If an electric current were passed over the wire 36, the magnet 35 would be energized and the pin 28 with- 110 drawn from back of the pawl 26, and the spring 27 would be permitted to swing the pawl 26 into the position shown in dotted lines in Fig. 13, whereupon the revolving gear 15 would carry with it the disk 24 and 115 the main shaft. In order to close the circuit to this magnet 35, the construction shown in Figs. 4, 9 and 10 may be employed. A current source 98 of any desired character connects to the ground 99 by means of a wire 100. This ground is preferably the frame 120 of the shear or its track. From the current source 98 a wire 102 connects to the plate 103 mounted on a bearing 87 adjacent the lever 90, which plate 103 is insulated in any de- 125 sired manner. Mounted on the lever 90 is a second contact plate 104, to which a wire 105 connects. This wire also connects to the contact plate 106, shown in Figs. 11 and 12, 130 which contact plate is connected on one of the

tracks 1. Mounted on one of the sides 5 is a contact plate 107 from which the wire 36 extends to the magnet 35. The other end of the winding of the magnet is grounded on the adjacent frame 5. The parts 103, 104, 106 and 107 are properly insulated. When therefore the sheet strikes the lever 89 or the lever 90, depending upon which edge of the sheet is in advance, the shaft 88 will be turned and the contact plate 104 will engage the contact plate 103, closing the circuit between the current source and the magnet 35. This will cause the pin 28 to be withdrawn, the pawl 26 to swing out into the path of the teeth 23 on the gear 15, and the main shaft 10 of the shear to turn. As soon as the shaft 10 begins to turn, the vertically slideable plate 7 descends and grips the sheet 59^a between it and the adjacent shear plate 47.

At practically the same instant that the plate 7 grips the sheet of fibrous material, the pressure in the cylinder 55 is sufficiently great to just about move the shear along on its ways, which will result in the shear and paper moving together. As soon as this occurs, the contact between the plates 106 and 107 will be broken and the electro-magnet 35 deenergized, permitting the spring 29 to move the pin 28 into the path of the pawl 26 so that when the shaft 10 has made one complete revolution, the gear 15 will be disconnected from it. This, and the brake 18, will cause the main shaft to stop in the desired position at the end of each revolution. The revolution of the main shaft 10 causes the cam 17 to depress the arms 50 and the plate 7 to grip the paper as before stated. Immediately afterward, the cranks 11 will depress the plate 8 and the shear member 9, which latter passes between the shear members 47 and severs the fibrous material along straight, parallel lines. The lower edge of this shear member 9 is preferably in the form of two inclines meeting at the center, as shown in Fig. 15. Immediately after the shearing is completed, the workmen lift the severed sheet from the machine. The forward end of the sheet will slide up over the upper ends of the levers 89 and 90, and hold these levers down until the sheet has been lifted off. The shear keeps on moving until the fingers 110 on the cross bar 85, shown in Fig. 6, engage a collar 111 on the valve rod 79 and move this valve rod outward to such position as will permit the air to pass into the front end of the cylinder through the port 78, whereupon the piston, piston rod and shear will be forced back to original position.

Many of the details of construction shown in the drawing may be changed without departing from the spirit of my invention. Thus the entire shearing mechanism may be removed and a different device substituted

so long as such new shear will operate at the proper time and may be moved with the sheet, all under control of the sheet.

I claim.

1. The combination of a track, a normally inoperative shear movable along the track and having a cutting member, electrically operated means for releasing the cutting members, mechanism for moving the shear along the track, means in the path of the sheet to be severed to control the mechanism, and a switch under the control of said sheet to close the circuit to said releasing means for the cutting member.

2. The combination of a track, a normally inoperative shear having cutting members transverse to the track, electrically operated means for releasing the cutting members, a pneumatic cylinder mounted on the track, a piston therein and a piston rod connecting to the shear, a valve to control the movement of the piston, means in the path of the sheet to be severed to actuate the valve, and a switch under the control of said sheet to close the circuit to said releasing means for the cutting members.

3. The combination of a track, a frame mounted thereon comprising two side members and a pair of cross bars, flat cutter bars mounted on the cross bars, a presser plate 95 and a shear plate vertically movable in said side members, a normally stationary main crank shaft and means operatively connecting the shaft to said vertically movable plates, a constantly running driving gear, a 100 connecting device between said gear and shaft, a pin to hold said connecting device inoperative, an electro-magnet for withdrawing the pin, a normally open circuit for said electro-magnet, and means under the 105 control of the article to be sheared to close said circuit and permit the operation of the shear.

4. The combination of a shear for a continuously moving sheet of fibrous material, 110 a track for the shear parallel to the direction of movement of said sheet, a pneumatic cylinder mounted on said track to move the shear along with the sheet and back to normal position after the sheet has been cut, 115 a valve for the cylinder, means in the path of the sheet for moving the valve to cause the shear to be moved with the sheet, and means operable by the shear when it has moved a predetermined distance to change 120 the position of the valve so that the shear shall be moved back to normal position.

5. The combination of a shear for a continuously moving sheet of fibrous material, a track for the shear, an electro-magnet to 125 control the actuation of said shear, a circuit therefor, a normally open and a normally closed switch in said circuit, a pneumatic cylinder connected to said shear to move the same with said sheet, a valve for said cylin- 130

der, means in the path of said sheet to close the normally open switch so that said shear will be actuated to sever the sheet and to move the valve to cause the cylinder to move the shear with the sheet during its actuation and thereby also open the normally closed switch, and means mounted on the shear to reverse the valve after the actuation of the shear so that the shear will be moved back to normal position.

6. The combination of a shear for a continuously moving sheet of fibrous material comprising two flat bars and a third bar movable down between the other two, an actuating mechanism for the movable bar, a normally inactive connector between them, electrically energized means to cause the connector to become operative, an electric circuit therefor having a normally open switch, means in the path of the sheet to be sheared to close the switch, and means controlled by said sheet to break said circuit immediately after the shear begins to operate.

25 7. The combination of a track, a shear for a continuously moving sheet of fibrous material, wheels supporting said shear and running on said track, a pneumatic cylinder mounted on the track and connected to said shear to move the shear back and forth along the track, a lever mounted on the track in the path of the sheet, a valve for said cylinder, and a rod connecting the lever and valve whereby the valve will be shifted when the sheet engages the lever.

40 8. The combination of a track, a shear for a continuously moving sheet of fibrous material, wheels supporting said shear and running on said track, a pneumatic cylinder mounted on the track and connected to said shear to move the shear back and forth along the track, a lever mounted on the track in the path of the sheet, a valve for said cylinder, a rod connecting the lever and valve whereby the valve will be shifted when the sheet engages the lever, an arm mounted on the shear, and a collar on said rod in the path of the arm whereby the valve will be shifted to normal position to cause the cylinder to move the shear back to starting position.

45 9. The combination of a shear longitudinally movable along the line of movement of a sheet or bar to be severed, a gripper for the sheet or bar, means for actuating the gripper to seize the sheet and means for thereafter actuating the shear to sever the sheet.

50 10. The combination of a shear movable along the line of movement of a sheet to be severed, a gripper for the sheet, means for actuating the gripper to seize the sheet, means for thereafter actuating the shear to sever the sheet, the means for actuating the gripper and the means for actuating the

shear being controlled by the movement of the sheet.

55 11. The combination of a shear, means for moving the shear along the line of movement of a sheet to be severed, a gripper for the sheet, means for actuating the gripper to seize the sheet, means for thereafter actuating the shear to sever the sheet, and means operated by the movement of the sheet for controlling the gripper and shear actuating means.

60 12. The combination of a shear, means for moving the shear along the line of travel of a sheet to be severed, a gripper for the sheet, means for actuating the gripper to seize the sheet, means for thereafter actuating the shear to sever the sheet, and a magnet energized by the movement of the sheet for controlling the gripper and shear actuating means.

65 13. The combination of a track, a normally inoperative shear movable along the track, a gripper for the sheet to be severed, means for actuating the gripper to seize the sheet and means for thereafter actuating the shear to sever the sheet.

70 14. The combination of a track, a normally inoperative shear movable along the track, a gripper for the sheet to be severed, means for actuating the gripper to seize the sheet, means for thereafter actuating the shear to sever the sheet, the means for actuating the gripper and the means for actuating the shear being controlled by the movement of the sheet.

75 15. The combination of a track, a normally inoperative shear movable along the track, a gripper for the sheet to be severed, means for actuating the gripper to seize the sheet, means for thereafter actuating the shear to sever the sheet, and means operated by the movement of the sheet for controlling the gripper and shear actuating means.

80 16. The combination of a track, a normally inoperative shear movable along the track, a gripper for the sheet to be severed, means for actuating the gripper to seize the sheet, means for thereafter actuating the shear to sever the sheet, and a magnet governed by the movement of the sheet for controlling the gripper and shear actuating means.

85 17. The combination of a track, a normally inoperative shear movable along the track, means for moving the shear along the track, a gripper for the sheet to be severed, a continually running motor for actuating the gripper and shear, gearing connecting the motor with the gripper and shear, said gearing comprising a one-revolution clutch, and means controlled by the movement of the sheet to actuate the clutch.

90 18. The combination of a track, a normally inoperative shear, means for moving the shear along the track, a gripper for the

sheet to be severed, a continually running motor for actuating the gripper and shear, gearing connecting the motor with the gripper and shear, said gearing comprising a 5 one-revolution clutch, an electro-magnet for controlling the clutch, a circuit for the magnet, and a switch operated by movement of the sheet for closing the circuit to energize the magnet.

10 19. The combination of a shear for a continuously moving sheet of fibrous material comprising two flat bars normally on one side of the sheet and a third bar movable

down between the other two from the other side of the sheet, an actuating member for 15 the movable bar, a normally inactive connector between them, and means in the path of the sheet to be sheared for controlling the movement of the actuating member.

In testimony whereof I have signed this 20 specification in the presence of two subscribing witnesses.

BEN K. FORD.
